FLUID CONTROL DEVICE

Wallace A. Hanson, Jr., Valley Hill Road, Rte. 1,
Riverdale, Clayton County, Ga.
Filed Mar. 15, 1963, Ser. No. 265,388
19 Claims. (Cl. 137—599.2)

This invention relates to a fluid control device and particularly to a control valve arrangement for a hydraulic pressure system, such as an elevator system, to control the rate of flow in response to control by an operator.

The present invention has a particular application in the field of hydraulic elevator apparatus and hydraulic elevator controls but is not specifically limited to this apparatus and may find other applications in hydraulic fluid control systems.

Hydraulic fluid pressure control systems are commonly used in various places at the present time in applications where the fluid pressure, which is obtained from a pump, is used for causing a load to ascend and then descend from a fixed point such as the ground. One particular hydraulic fluid control system is in building elevators where the elevator cage is supported by a piston—the length depending upon the height of the building—which piston is confined in a jack cylinder that normally is submerged in the ground beneath the building. Fluid pressure provided by a pump is forced into the jack cylinder beneath the piston to cause the piston to be driven upwardly to raise the elevator cage therewith and there being electrically controlled valving to allow the fluid pressure of the supported load to be relieved and to bleed off or drain from the jack cylinder back into the system at a particular rate of flow so as to lower the elevator and cage. Normally the apparatus is controlled from within the cage by electrically operated manual control devices, either buttons, toggle handles or other apparatus, and there also may be secondary or emergency controls located in other places. Conventionally, the down flow control is governed by a flow control valve or hydraulic arrangement which receives the fluid in some manner in order to affect the fluid pressure and the rate of flow as applied to the piston to lower the elevator cage in a particular manner at a particular rate of flow.

Obviously, it is desirable to achieve a rapid rate of rise in the elevator so as to bring the elevator cage upwardly to the desired level as rapidly as consistent with physical factors, such as the ability of average humans to withstand sudden changes in speed; and in reverse it is desirable to lower the elevator as rapidly as possible consistent with safety and again with the human factor, such as the effect it has on an average human being in the elevator cage to lower it at a certain rate of speed. In a typical system the speed of reverse or downward travel will change in ratio with respect to the square root of the load. Also, the number of passengers and the load in the elevator is changing from time to time and the load itself is a dead load starting from a stopped position and becomes a live load as it picks up speed.

Since elevators normally must stop within a fraction of an inch or so of the level of the floor it is necessary, within a degree of time limitation, to effect a stopping of the elevator either on the upward or downward travel thereof and to level same as rapidly as possible bringing it to a smooth stop at the proper position. The problem involved in doing this increases materially as the speed of the elevator is increased. For example, it is simpler to raise and lower and level an elevator which travels at a very low rate of speech such as forty (40) feet a minute as compared with stopping and leveling the same elevator which is traveling at a speed approaching 200

feet a minute and having to adjust to a secondary speed in order to approach the landing and to level therat.

Various fluid valve control apparatuses are known in the prior art specifically for governing and regulating elevator control apparatus of the sort also contemplated by the present invention. Some valve control devices use a piston assembly and control a piston assembly in two different positions to obtain two different flow rates. Others use two independent and separate valves in parallel and sequenced to obtain two flow rates. It is to be noted that the present invention provides an arrangement of two different size pistons in an internal valve body itself with the secondary flow rate or the leveling speed piston traveling with the main flow piston to be opened upon closing of the main flow piston to provide two different flow rates in the desired sequence.

One of the great difficulties in obtaining satisfactory operation of the sort of control employing one piston controlled in two different positions to obtain two different flow rates is controlling the deceleration rate from high speed to leveling speed and still being able to stop the elevator at the floor level with accuracy. Prior art devices provide in some instances a satisfactory stopping arrangement but the elevator will drift at the floor because of the necessity of filling too large a piston area and there is not a proper cut-off of the flow at leveling speed for prompt and accurate leveling at the floor.

The present invention overcomes the difficulty previously described in the preceding paragraph and accomplishes this in one embodiment by having two different sizes of pistons which may be considered a leveling or secondary flow piston and a main piston with the leveling piston of a smaller area relative to the main flow piston thereby accomplishing a much sharper cut-off for accuracy of leveling without sacrificing deceleration control.

An object of the present invention is to provide an improved arrangement in a hydraulic control for controlling a hydraulic elevator or similar hydraulic apparatus in such a manner that the leveling speed control is rapid and accurate and provides a comfortably sharp cut-off for accuracy of rapid leveling.

A further object of this invention is to provide in a hydraulic control apparatus for a hydraulic elevator system or the like a primary control piston mounted for movement in the valve and a secondary flow piston traveling therewith and having a smaller area relative thereto to provide a comfortably sharp control for accuracy of leveling.

Still another object of this invention is to provide a compact and composite hydraulic control valve system employing a primary control piston mounted for movement axially of the main body of the valve and having mounted therein a secondary control piston co-axial therewith and mounted for relative movement thereto and to travel therewith to provide a rapid cut-off of the controlled flow for leveling.

A further object of this invention is to provide in a hydraulic control apparatus for an elevator or the like in which there is according to the present invention a pair of hydraulic pistons mounted for relative movement with respect to the valve body and with respect to each other, one of said pistons being smaller than the other, a pair of solenoid valve controls, one for the main control piston and the other for the secondary or smaller control piston, whereby more rapid and accurate deceleration is obtained for leveling and stopping.

A further object of my invention is to house a control means in a compact, integral body to simplify installation and service.

Another advantage of the apparatus in the preceding paragraph is to obtain a comfortable and practically step-

less deceleration from main flow into secondary flow; and also, to provide a valve that can set up a secondary flow without going through a complete sequence.

FIG. 1 is a diagrammatic view of a hydraulic elevator system illustrating diagrammatically the principal components thereof and showing in central, longitudinal cross-section the valve control apparatus of the present invention and including diagrammatically the pair of solenoid valve control members.

FIG. 2 is a cross-section view the same as shown in FIG. 1 but with the valve changed by fluid flow to indicate a condition existing when the elevator cage is leveling down.

FIG. 3 is a view the same as that shown in FIGS. 1 and 2 except that the valve is changed to indicate a condition existing when the cage is moved from a floor position other than the lowermost floor position to establish the down speed of the cage.

FIG. 4 is a view the same as those shown in FIGS. 1 through 3 but illustrating a modified form of the invention, using an optional pilot solenoid valve to obtain secondary flow.

Initially, by way of general environment and background material, a typical hydraulic installation which represents an elevator system is shown in FIG. 1 comprising, diagrammatically, an elevator cage 12, the details of which are well known, supported on a rigid piston 14 operating in a submerged cylinder or jack cylinder 16 which has conventional fluid packing and ring seal arrangement 18 between the piston 14 and cylinder 16. An input fluid line 20 leads into the cylinder 16 to provide fluid pressure beneath the piston 14 and to drain fluid and relieve fluid pressure beneath the piston 14, respectively, for raising or lowering piston 14 and the elevator cage 12 which travels in a building structure 22 having floor positions 24 at which the elevator stops periodically.

Still by way of background material a conventional pump 26 is power driven as shaft 28 by any suitable means such as an electric motor (not shown) and may be of the constant displacement type. Pump 26 supplies fluid under pressure to the whole system and which fluid ultimately is applied with pressure through the line 20 to the bottom of piston 14 to raise same in the manner previously described. A fluid reservoir 30 contains a supply of hydraulic fluid 32 which is supplied through an outlet 34 to the inlet portion of pump 26 and which in turn is supplied through the input line 36 to the whole system. Check valve 35 maintains system pressure when the pump 26 is at rest. A fluid return line 40 returns fluid from the valve control device 42 of the present invention to the reservoir 30.

Electrically operated control devices 44 which may be contained in and on the cage 12 of the elevator and also attached to building structure 22 normally are electrically operated to operate the solenoid controls of the present invention in a manner which is well known in the controls field and does not per se form a part of this invention. It is considered sufficient to state that these controls contain some switch means to operate a circuit or circuits which in turn electrically operate the solenoid valve control devices.

Valve control device 42 consists of a barrel-like housing 48 having an outlet 50 formed thereon which leads to the fluid reservoir 30. Valve 42 has a compartment 52 formed in the interior thereof in which is mounted a primary or main flow control piston 54 of circular configuration with an annular periphery 56 for sliding engagement with the interior circular wall of compartment 52 and having a nose portion 58 in which is formed radial openings 60 through which fluid may pass from a high pressure inlet line 38 such being connected with the line 20. The nose portion 58 of piston 54 is formed with a protruding cylindrical outlet 62 having orifices or openings 64 formed therein and leading into the barrel-like outlet 62. A

cap member 68 closes the rear compartment 52 and the rear portion of the valve member 42 and housing 50 and is fastened in place by a number of screws 70.

Cap 68 has a longitudinal bore 72 therein co-axial with the longitudinal axis of the barrel portion 62 and the housing 50 and co-axial with respect to the main flow control piston 54. Mounted for movement in the bore 72 and a bore 74 formed in alignment therewith and co-axial therewith through the piston 54 is a leveling or secondary flow control piston 76 having a longitudinal bore 79 therein co-axial with respect to the axis of the housing 50 and with respect to the axis of piston 54. The front portion 80 of piston 76 is reduced in diameter to allow the flow of fluid as will be described hereinafter. An annular stop ring member 78 is mounted on the piston 54 and encircling the secondary piston 76 to engage a shoulder 81 on the secondary piston 76 after it has unseated and traveled a certain distance. An adjustment screw member 82 is threadedly engaged in the bore 79 of secondary piston 76 to receive selectively an adjustment screw driver member 84 reciprocally mounted therein in bore 73 of a cylindrical adjustment sleeve 90 which is threadedly engaged in a reduced opening and bore 86 in the cylindrical end 88 of the cap 68. Cylindrical adjustment sleeve 90 is mounted for movement in the bore 86 and threadedly engages the cylindrical portion 88 and has a slotted end 92 thereon.

An ordinarily screw driver may be inserted in the slotted end 94 of screw driver adjustment member 84 and it may be pushed forward to engage the slotted end 96 of the adjustment member 82 for the purpose of turning same to adjust the secondary flow rate. Similarly, a screw driver may be inserted in the slotted end 92 of the member 90 and it may be selectively rotated inwardly or outwardly to place the end portion 95 in a different position to adjust the extent of movement of the primary piston 54 as it travels rearwardly carrying the secondary piston 76 therewith. A first solenoid control valve 100 comprises a movable armature 102 in a housing 104 to which is connected a pilot flow control line 106 leading through the body of 42 into the high pressure line 38.

A second solenoid control valve 108 comprises an armature 110 movable in a body 112 selectively to open and control a pilot flow control line 114 extending through the cap 68 into the compartment 52 behind piston 54.

An outlet line 116 extends from the solenoid control valve body 112 back to the reservoir 30. Another outlet 118 extends from the outlet end on solenoid 100 from body 104 back to the reservoir 30.

Normally, line pressure is maintained from line 20 through line 38 into the valve body 50 and there is no flow of fluid when the main flow control pilot solenoid 108 and the secondary flow control pilot solenoid 100 are de-energized.

Assuming that the piston 14 and the elevator cage 12 is at the floor position 24 other than the uppermost position and in response to the aforementioned electrically operated control devices 44, the elevator cage 12 is propelled upward by pump 26 toward a desired floor position 24 at which a stop is to be made. If the cage 12 overshoots the floor position 24 (either by design or malfunction) but remains within the distance conventionally known as the leveling zone, the solenoid control valve 100 will be energized by a switch in the passage. (Refer to FIG. 2.) Armature 102 will thus block line 106 and open a passageway from line 99 thru valve 100 to line 118 thereby bleeding bore 72 to reservoir 30 pressure. This change of pressure in bore 72 creates an unbalanced force on secondary piston 76 as the front portion 80 has line pressure exerted upon the annular area exposed between the outside diameter of piston 76 and its seat 77. This unbalanced force moves piston 76 rearward until it is restrained by stop ring 78 which results in the secondary flow being established from line 38 thru openings 60 by seat 77 and on thru port 55 in the main flow piston 54.

into line 40 into reservoir 30. Note that this flow may be regulated by adjusting screw 82 in and out to restrict this flow passageway. The secondary flow continues until the cage 12 has leveled downward to the floor position 24 and the solenoid valve 109 is de-energized. Variable orifice 105 may be used to control the pilot flow rate to reclose piston 76 to its closed position with seat 77 blocking port 55. Likewise, variable orifice 107 may be used to control the pilot flow rate allowing piston 76 to move to its open position.

Further assuming that the piston 14 and the elevator cage 12 is at a floor position 24 other than the lowermost position, and in response to the aforementioned electrically operated control devices 44, solenoid valve 108 is energized (refer to FIG. 3), thus establishing a pilot flow from line 38 thru line 106 thru variable orifice 117 thru line 109 into compartment 52 out line 114 thru variable orifice 115 into valve 108 past armature 110 on thru line 116 back to the reservoir 30. Now if variable orifice 115 is preadjusted more open than variable orifice 117, this pilot flow will sufficiently reduce the pressure in compartment 52 so that the resulting imbalance on piston 54 will cause this piston 54 to move rearward. Note that line pressure from line 38 creates this imbalance on the annular area extending from the seat 57 to the periphery 56. Piston 54 moves rearward until the rear end of piston 76 strikes the end portion 95 of member 90. Thus, with seat 57 opening port 59, the main flow is established from line 38 by seat 57 thru openings 64 out outlet 62 into line 40 onto reservoir 30. This rate of flow is regulated by adjusting member 90 in and out, thereby establishing the down speed of cage 12. Cage 12 continues downward until at a predetermined distance above floor position 24 at which the desired stop is to be made, the aforementioned electrically operated control devices 44 de-energizes valve 108 and at or about the same time energizes valve 109. With the pilot flow thru valve 108 stopped, the continuing pilot flow thru line 106 thru variable orifice 117 thru line 109 into compartment 52 increases the pressure in compartment 52 until there is an imbalanced force on piston 54 to move it forwardly until seat 57 closes off the flow. In practice, variable orifice 117 would be adjusted to obtain an acceptable deceleration from full-speed down into leveling speed and then variable orifice 115 adjusted for proper acceleration from the at rest condition into full-speed down. Upon de-energization of valve 108 and energization of valve 109, the resulting imbalanced force on piston 76 holds piston 76 against member 90 until retaining ring 78 strikes shoulder 81 and then piston 76 moves forward along with piston 54 that is closing. This results in the cage 12 decelerating from full speed down into leveling speed. Cage 12 continues leveling down until when at floor position 24 the aforementioned electrically operated control device 44 de-energizes valve 109 and piston 76 closes leaving the system at rest.

Secondary flow can also be achieved using an optional pilot solenoid valve 140 in conjunction with valve 108 as shown in FIG. 4. Operation is the same as above described and main flow is shown in FIG. 3 and ascribed in connection therewith.

Operation can also be achieved with proper piston 54 and piston 76 area proportions if solenoid valve 109 and 108 and/or 140 and 108 are energized simultaneously to obtain full down speed and then de-energizing 108 to change into leveling speed leaving 109 or 140 energized until floor position 24 is reached.

While I have shown and described a particular embodiment of my invention together with suggested operation thereof and a typical modification, this is by way of illustration only and is not to be construed as any sort of limitation on the scope of my invention since various alterations, changes, deviations, substitutions, eliminations, and ramifications may be made in the invention shown

and described without departing from the scope of the invention as defined in the appended claims.

I claim:

1. In a control valve for controlling the flow in a fluid pressure system such as a control system for controlling the descent and leveling of an elevator in a hydraulic system in which there is a jack cylinder and elevator piston operated by fluid delivered under pressure from a fluid reservoir,

- 10 (a) a valve housing having a chamber therein with an outlet leading to the reservoir and an inlet to said valve from the pressure line,
- (b) first control means in said valve having a throttled orifice closing said pressure inlet from said outlet to control the flow of fluid effective from said jack cylinder,
- (c) a second control member in said valve operable independently of said first control member and closing a smaller orifice leading from said pressure inlet to said outlet,
- (d) first control means actuatable to cause an imbalance on said second control means thereby to cause a reduced and throttled flow through said orifice normally closed by said second control means to establish a leveling speed.

- (e) second control means actuatable to cause an imbalance on said first control means to establish a main flow,
- (f) and said first and second control means being operable to cause said first and second member to return to closed position to bring said system to rest.

2. In a control valve for controlling the flow in a fluid pressure system such as a control system for controlling the descent and leveling of an elevator in a hydraulic system in which there is a jack cylinder and elevator piston operated by fluid delivered under pressure from a fluid reservoir,

- (a) a valve housing having a chamber therein with an outlet leading to the reservoir and an inlet to said valve from the pressure line,
- (b) first control means in said valve having a throttled orifice closing said pressure inlet from said outlet to control the flow of fluid effective from said jack cylinder,
- (c) a second control member in said valve mounted coaxially with and operable independently of said first control member and closing a smaller orifice leading from said pressure inlet to said outlet,
- (d) and means to imbalance said first and second control means in desired sequence thereby to establish selectively a down flow by said first control means and a leveling flow by said second control means.

3. In a control valve for controlling the flow in a fluid pressure system such as a control system for controlling the descent and leveling of an elevator in a hydraulic system in which there is a jack cylinder and elevator piston operated by fluid delivered under pressure from a fluid reservoir,

- (a) a valve housing having a chamber therein with an outlet leading to the reservoir and an inlet to said valve from the pressure line,
- (b) first control member sealed in said valve having a throttled orifice closing said pressure inlet from said outlet to control the flow of fluid effective from said jack cylinder,
- (c) a first chamber for said first control member (b),
- (d) a second control member in said valve operable independently of said first control member and closing a smaller orifice leading from said pressure inlet to said outlet,
- (e) a second chamber on said second control (d),
- (f) first control means actuatable to cause an imbalance in said second chamber on said second control member thereby to cause a reduced and throttled

- leveling flow through said orifice normally closed by said second control means,
- (g) a second control means actuatable to cause an imbalance on said first control member to open and close selectively said main flow thereby to control the down flow,
- (h) said means (f) and (g) being operable sequentially and selectively to travel up and down and level.
4. The device in claim 3 wherein both of said control means (f) and (g) are solenoid controlled.
5. The device in claim 4 wherein both of said solenoid controlled means in (f) and (g) are valves that selectively vary the pressure in the chambers (c) and (e) to cause the imbalance.
6. In a control valve for controlling the flow in a pressure fluid system such as a control system for controlling the descent and leveling of an elevator by a hydraulic system in which there is a jack cylinder and elevator piston operated by fluid delivered under pressure from a fluid reservoir,
- (a) a valve housing having a chamber therein with an outlet leading to the reservoir and an inlet to said chamber leading from the pressure line,
- (b) a first control member in said chamber normally sealing a larger but throttled orifice between said pressure inlet and said outlet and sealing same around the periphery and said main control member being sealed for movement in said chamber with fluid effective in more than one direction thereon,
- (c) a smaller orifice leading from said high pressure inlet of said chamber in said valve and to said outlet and normally being closed by a
- (d) second control member movably mounted in said chamber and having a portion thereof effected by the pressure from said fluid inlet but normally in one position thereof being balanced to close said smaller orifice,
- (e) a second chamber in said valve having a portion of the second control member therein and adapted normally to balance the pressure on said second control member to close said smaller orifice,
- (f) first solenoid valve control means selectively and electrically operated to bleed a small amount from said second chamber thereby to cause an imbalance on said second member causing said second member to unseat from the smaller orifice and thereby permitting a small amount of throttled flow therethrough,
- (g) said throttled flow in the above mentioned paragraph permitting the movement of the elevator in a controlled, reduced movement to the desired location,
- (h) said first control member remaining balanced to close the larger throttled flow while said smaller throttled flow is in operation,
- (i) second control means operable to reduce the pressure in one direction on said first control member to permit said first control member to be overbalanced by pressure from the other direction thereby to open said larger orifice to operate the throttled faster down speed of the elevator,
- (j) said first and second controls being operably and selectively sequenced to cause said second control member to open said smaller and pilot flow for leveling said elevator or the like and thence to open said main throttled control flow for proper down speed and thereafter to sequence said first control to close said main down speed but to permit said second control member to remain open thereby to shift smoothly from throttled down speed to throttled leveling speed to bring said elevator to a smooth proper leveled position.
7. In an elevator control valve for controlling the descent and leveling of an elevator by a hydraulic control system in which there is a jack cylinder and elevator

piston operated by fluid delivered under pressure and from a fluid reservoir;

- (a) a valve housing having an inlet therein to receive the fluid under pressure from the fluid pressure means and having an outlet therein to exhaust fluid to the fluid reservoir,
- (b) and wherein said fluid inlet is normally a higher pressure flow than said lower pressure fluid outlet,
- (c) a valve chamber within said valve housing in communication with both said inlet and said outlet,
- (d) first means in said valve chamber communicating said chamber with said inlet and outlet and adapted to move therein to close said inlet from said outlet, and including
- (e) a variable orifice moving with said means (d) to vary the opening between said inlet and said outlet through said chamber,
- (f) a second chamber formed within said first control member and having a first control passageway leading from said inlet into said chamber and a first outlet passageway leading from said second chamber to said chamber in said housing on one side of said first control member,
- (g) a second means having a portion thereof engageable in the variable outlet orifice of said first control member to seal same in one position thereon and to open same upon movement,
- (h) said second means having a portion thereof sealed from and communicated with the first inlet passage in said first control member and the first outlet passage in said control member,
- (i) adjustable means on said first control member operable to stop second control member upon the movement of same after it has moved out of the variable orifice,
- (j) said adjustable means (i) being adjusted to vary the rate at which said second means opens said variable orifice,
- (k) said chamber in said valve housing being defined by said first control means into a chamber portion on one side of said first control means and the chamber portion on the other side thereof within said valve housing,
- (l) a first by-pass control passage leading from said high pressure inlet to the inlet of,
- (m) a first control solenoid member having an outlet thereon leading to the reservoir,
- (n) a second by-pass passage leading from said first by-pass line into said valve chamber, and
- (o) a second solenoid having an outlet to the reservoir and an inlet from said chamber.
8. In a control valve for controlling the flow in a pressure fluid system such as a control system for controlling the descent and leveling of an elevator by a hydraulic system in which there is a jack cylinder and elevator piston operated by fluid delivered under pressure from a fluid reservoir,
- (a) a valve housing having a cylindrical chamber therein with an outlet leading to the reservoir and inlet to said chamber leading from the pressure line,
- (b) a first control member mounted in said chamber and being sealed therein to separate said chamber into more than one compartment having fluid therein operable against different sides of said member,
- (c) said member in (b) having a variable orifice for the purpose of throttling the flow of fluid from said inlet pressure line through said chamber and from said outlet,
- (d) a second control member mounted in said chamber and having a portion thereof adapted to close an orifice leading from said pressure side of the compartment through said throttled orifice in said first member,
- (e) a reduced passage leading from said pressure line to said second control member and normally being

- blocked thereby to prevent said pressure fluid from exiting through said reduced orifice normally sealed by said second member,
- (f) a second chamber in said valve housing sealed from said first chamber and the separate compartments therein and having a portion of the second control member confined therein to be acted upon by the change in pressure in said second compartment,
- (g) a control by-pass line leading from said high pressure line to said compartment in said first chamber on the side of said first control member opposite from the outlet orifice side and said by-pass line also leading to the inlet of a
- (h) solenoid control valve electrically operable from a remote point to close said valve and having an outlet line leading to said reservoir which outlet is opened and closed by said solenoid valve,
- (i) said solenoid valve having a second by-pass line leading therefrom adapted to be closed when said high pressure inlet is closed and to be opened when said first solenoid outlet is closed,
- (j) said second line from said first solenoid leading to the said second chamber in said valve housing to bear the pressure on said second control member in response to the change of
- (k) a third by-pass leading from said compartment in said first chamber opposite from the outlet compartment to a
- (l) second solenoid control valve having a control therein adapted to open and close said third by-pass and having an outlet therein leading to said reservoir,
- (m) said second solenoid simultaneously closing both said high pressure inlet thereto and said outlet to the reservoir and vice versa opening said inlet to said outlet when operated,
- (n) whereby in one sequence of operation from an at-rest position the smaller orifice initially is opened to a throttled main flow by the energization of said first solenoid and thereafter upon energization of said second solenoid said first control member is operated to open said throttled main flow through said main control orifice.
9. In a control valve for controlling the flow in a pressure fluid system such as a control system for controlling the descent and leveling of an elevator by a hydraulic system in which there is a jack cylinder and elevator piston operated by fluid delivered under pressure from a fluid reservoir,
- (a) a valve housing having a cylindrical chamber therein with an outlet leading to the reservoir and an inlet to said chamber leading from the pressure line,
- (b) a first control piston mounted in said chamber being sealed in said chamber around the periphery thereof and defining said chamber into separate compartments on opposite sides of said piston,
- (c) said piston having a variable orifice control mounted in said outlet and adapted to move in and out thereof to control the rate of flow therethrough,
- (d) a second piston mounted co-axially with a portion inside of said first piston and being sealed around the periphery thereof to separate the interior of said first piston into opposite chambers,
- (e) a control passageway leading from said high pressure inlet to the interior of said second piston on one side of said first piston,
- (f) said second piston normally closing a second orifice leading from the interior of said first piston,
- (g) a first by-pass line leading from the high pressure inlet to
- (h) a solenoid controlled valve having an outlet leading to said reservoir,
- (i) a second control by-pass leading from said first control by-pass into the chamber of said valve hous-

ing on the side of said first piston opposite from said variable orifice,

- (j) stop means for stopping the movement of said first piston,
- (k) second stop means for stopping the movement of said first piston,
- (l) a third by-pass line leading from said portion of said chamber opposite from said variable orifice outlet to a
- (m) second solenoid control valve having an outlet leading to said reservoir,
- (n) a third chamber formed in said housing on the side of said second piston opposite from said variable orifice of said first piston and there being,
- (o) a fourth by-pass line leading from the high pressure side of said first solenoid control valve into said chamber communicative with said second piston.

10. In a control valve for controlling the flow in a pressure fluid system such as a control system for controlling the descent, and leveling of an elevator by a hydraulic system in which there is a jack cylinder and elevator piston operated by fluid delivered under pressure from a fluid reservoir,

- (a) a valve housing having a cylindrical chamber therein with an outlet leading to the reservoir and an inlet to said chamber leading from the pressure line,
- (b) a first control piston mounted in said chamber being sealed in said chamber around the periphery thereof and defining said chamber into separate compartments on opposite sides of said piston,
- (c) said piston having a variable orifice control mounted in said outlet and adapted to move in and out thereof to control the rate of flow therethrough,
- (d) a second piston mounted co-axially with a portion inside of said first piston and being sealed around the periphery thereof to separate the interior of said first piston into opposite chambers,
- (e) a control passageway leading from said high pressure inlet to the interior of said second piston on one side of said opposed chambers adjacent said variable outlet orifice of said first piston,
- (f) said second piston normally closing a second orifice leading from the interior of said first piston,
- (g) a first by-pass line leading from the high pressure inlet to
- (h) a solenoid controlled valve having an outlet leading to said reservoir,
- (i) a second control by-pass leading from said first control by-pass into the chamber of said valve housing on the side of said first piston opposite from said variable orifice,
- (j) stop means for stopping the movement of said first piston,
- (k) second stop means for stopping the movement of said first piston,
- (l) a third by-pass line leading from said portion of said chamber opposite from said variable orifice outlet to a
- (m) second solenoid control valve having an outlet leading to said reservoir,
- (n) a third chamber formed in said housing on the side of said second piston opposite from said variable orifice of said first piston and there being,
- (o) a fourth by-pass line leading from the high pressure side of said first solenoid control valve into said fourth chamber recited in paragraph
- (p) and solenoid control valves selectively for bleeding said chambers.

11. In an elevator control valve for controlling the descent and leveling of an elevator by a hydraulic control system in which there is a jack cylinder and elevator piston operated by fluid delivered under pressure and from a fluid reservoir,

- (a) a valve housing having an inlet therein to receive

- the fluid under pressure from the fluid pressure means and having an outlet therein to exhaust fluid to the fluid reservoir,
- (b) and wherein said fluid inlet is normally a higher pressure flow than said lower pressure fluid outlet, 5
- (c) a valve chamber within said valve housing in communication with both said inlet and said outlet,
- (d) a first control member movably sealed in said chamber and arranged to communicate said chamber with said inlet and outlet and adapted to move 10 therein to close said inlet from said outlet,
- (e) a variable orifice formed on said first control member and adapted to move with said control member to vary the opening between said inlet and said outlet through said chamber, 15
- (f) a second chamber formed within said first control member and having a first control passageway leading from said inlet into said chamber and a first outlet passageway leading from said second chamber to said chamber in said housing on one side of 20 said first control member,
- (g) a second control member mounted for movement relative to said first control member and having a portion thereof engageable in the variable outlet orifice of said first control member to seal same in one 25 position thereof and to open same upon movement,
- (h) said second control member having a portion thereof sealed from and communicated with the first inlet passage in said first control member and the first outlet passage in said control member, 30
- (i) adjustable stop means on said first control member engageable with said second control member to stop the movement of same after it has moved out of the variable orifice,
- (j) said adjustable means being adjusted to vary the 35 rate at which said second control member opens said variable orifice,
- (k) said chamber in said valve housing being defined by said first control means into a chamber portion on one side of said first control means and the chamber portion on the other side thereof within said valve housing,
- (l) a first by-pass control passage leading from said high pressure inlet to the inlet of, 40
- (m) a first control solenoid member having an outlet thereon leading to the reservoir, and
- (n) a second by-pass passage leading from said first by-pass line into said second chamber,
- (o) and solenoid controlled valves to selectively bleed 45 said chambers through said by-pass lines.
12. In a control valve for controlling the flow in a pressure fluid system such as a control system for controlling the descent and leveling of an elevator by a hydraulic system in which there is a jack cylinder and elevator piston operated by fluid delivered under pressure from a fluid reservoir, 50
- (a) a valve housing having a chamber therein with an outlet leading to the reservoir and an inlet to said chamber leading from the pressure line,
- (b) a first control member in said chamber normally sealing a larger but throttled orifice between said pressure inlet and said outlet and sealing same around the periphery and said main control member being sealed for movement in said chamber with fluid effective in more than one direction thereon, 55
- (c) a smaller orifice leading from said high pressure inlet of said chamber in said valve and to said outlet and normally being closed by a
- (d) second control member movably mounted in said chamber and having a portion thereof effected by the pressure from said fluid inlet but normally in one position thereof being balanced to close said smaller orifice, 70
- (e) a second chamber in said valve having a portion of the second control member therein and adapted 75

- normally to balance the pressure on said second control member to close said smaller orifice,
- (f) first solenoid valve control means selectively and electrically operated to bleed a small amount from said second chamber thereby to cause an imbalance on said second member causing said second member to unseat from the smaller orifice and thereby permitting a small amount of throttled flow therethrough,
- (g) said throttled flow in the above mentioned paragraph permitting the movement of the elevator in a controlled, reduced movement to the desired location,
- (h) said first control member remaining balanced to close the larger throttled flow while said smaller throttled flow is in operation,
- (i) second control means operable to reduce the pressure in one direction on said first control member to permit said first control member to be overbalanced by pressure from the other direction thereby to open said larger orifice to operate the throttled faster down speed of the elevator,
- (j) said first and second controls being operably and selectively sequenced to cause said second control member to open said smaller and pilot flow for leveling said elevator or the like and thence to open said main throttled control flow for proper down speed and thereafter to sequence said first control to close said main down speed but to permit said second control member to remain open thereby to shift smoothly from throttled down speed to throttled leveling speed to bring said elevator to a smooth proper leveled position.
13. In a control valve for controlling the flow in a fluid pressure system such as a control system for controlling the descent and leveling of an elevator in a hydraulic system in which there is a jack cylinder and elevator piston operated by fluid delivered under pressure from a fluid reservoir,
- (a) a valve housing having a chamber therein with an outlet leading to the reservoir and an inlet to said valve from the pressure line,
- (b) first control means in said valve having a throttled orifice closing said pressure inlet from said outlet to control the flow of fluid effective against said jack cylinder,
- (c) a second control member in said valve operable independently of said first control member and closing a smaller orifice leading from said pressure inlet to said outlet,
- (d) first control means actuatable to cause an imbalance on said second control means thereby to cause a reduced and throttled flow through said orifice normally closed by said second control means,
- (e) a chamber having only a portion of said second control member therein,
- (f) a chamber defined by said first control and having a bleed line therein,
- (g) and electrically controlled means selectively for varying the pressure in the chambers (e) and (f) thereby to establish regular and leveling flow.
14. In a control valve for controlling the flow in a pressure fluid system such as a control system for controlling the descent, and leveling of an elevator by a hydraulic system in which there is a jack cylinder and elevator piston operated by fluid delivered under pressure from a fluid reservoir,
- (a) a valve housing having a cylindrical chamber therein with an outlet leading to the reservoir and inlet to said chamber leading from the pressure line,
- (b) a first control member mounted in said chamber and being sealed therein to separate said chamber into more than one compartment having fluid therein operable against different sides of said member,
- (c) said member in (b) having a variable orifice for

- the purpose of throttling the flow of fluid from said inlet pressure line through said chamber and from said outlet,
- (d) a second control member mounted in said chamber and having a portion thereof adapted to close an orifice leading from said pressure side of the compartment through said throttled orifice in said first member, 5
- (e) a reduced passage leading from said pressure line to said second control member and normally being blocked thereby to prevent said pressure fluid from exiting through said reduced orifice normally sealed by said second member, 10
- (f) a second chamber in said valve housing sealed from said first chamber and the separate compartments therein and having a portion of the second control member confined therein to be acted upon by the change in pressure in said second compartment, 15
- (g) a control by-pass line leading from said high pressure line to said compartment in said first chamber on the side of said first control member opposite from the outlet orifice side and said by-pass line also leading to the inlet of a
- (h) solenoid control valve electrically operable from a remote point to close said valve and having an outlet line leading to said reservoir which outlet is opened and closed by said solenoid valve, 25
- (i) said solenoid valve having a second by-pass line leading therefrom adapted to be closed when said high pressure inlet is closed and to be opened when said first solenoid outlet is closed, 30
- (j) said second line from said first solenoid leading to the said second chamber in said valve housing to bear the pressure on said second control member in response to the change of 35
- (k) a third by-pass line leading from said compartment in said first chamber opposite from the outlet compartment to a
- (l) second solenoid control valve having a control therein adapted to open and close said third by-pass line and having an outlet therein leading to said reservoir, 40
- (m) said second solenoid simultaneously closing both said high pressure inlet thereto and said outlet to the reservoir and vice versa opening said inlet to said outlet when operated, 45
- (n) whereby in one sequence of operation from an at-rest position the smaller orifice initially is opened to a throttled main flow by the energization of said first solenoid and thereafter upon energization of said second solenoid said first control member is operated to open said throttled main flow through said main control orifice, 50
15. In an elevator control valve for controlling the descent and leveling of an elevator by a hydraulic control system in which there is a jack cylinder and elevator piston operated by fluid delivered under pressure and from a fluid reservoir, 55
- (a) a valve housing having an inlet therein to receive the fluid under pressure from the fluid pressure means and having an outlet therein to exhaust fluid to the fluid reservoir,
- (b) and wherein said fluid inlet is normally a higher pressure flow than said low pressure fluid outlet, 60
- (c) a valve chamber within said valve housing in communication with both said inlet and said outlet,
- (d) first control means in said valve chamber communicating said chamber with said inlet and outlet and in one direction adapted to increase the flow through said outlet and in the other direction adapted to restrict the flow, 70
- (e) an orifice normally closed by the operation of said first means, 75

- (f) a second control means on said valve having a portion thereof in communication with said inlet in certain positions thereof and arranged to close selectively a secondary flow orifice independently of said primary flow orifice controlled by said first control means,
- (g) a first solenoid control valve means for changing pressure causing motion of said secondary flow means to operate said secondary control in said orifice as when leveling said elevator,
- (h) secondary solenoid control valve means actuatable to operate said secondary flow control, and
- (i) first solenoid control means actuatable to operate said first control means thereby to open said main flow as when said elevator is thereby establishing the down speed of the elevator.
16. In a control valve for controlling the flow in a pressure fluid system such as a control system for controlling the descent and leveling of an elevator by a hydraulic system in which there is a jack cylinder and elevator piston operated by fluid delivered under pressure from a fluid reservoir,
- (a) a valve housing having a chamber therein with an outlet leading to the reservoir and an inlet to said chamber leading from the pressure line,
- (b) said chamber having a first variable orifice formed therein with means thereon to pre-adjust same differently than a
- (c) second variable orifice in said chamber,
- (d) first control means in said chamber operated by an imbalance of pressure thereon to move from a main line flow to a restrictive flow position,
- (e) a pilot flow means on said chamber to cause an imbalance on said first control in response to a
- (f) first solenoid control means for said pilot flow,
- (g) means for adjusting the rate of flow of said first control means,
- (h) said first control means opening in response to said first solenoid to establish the down speed of the elevator,
- (i) a second solenoid control valve,
- (j) a second pilot flow through said second solenoid control valve operable at the time said first control valve is de-energized to change the imbalance force on said first control means to cause same to close off the main flow,
- (k) means operable upon the energization of said first solenoid control valve and energization of said second control valve to cause an imbalance on said secondary control means to open the secondary flow thereby to permit said elevator to decelerate from full down speed to leveling speed, and
- (l) said elevator continued to level down until the second solenoid control valve is operated to bring said system to rest.
17. In an elevator control valve for controlling the descent and leveling of an elevator by a hydraulic control system in which there is a jack cylinder and elevator piston operated by fluid delivered under pressure and from a fluid reservoir,
- (a) a valve housing having an inlet therein to receive the fluid under pressure from the fluid pressure means and having an outlet therein to exhaust fluid to the fluid reservoir,
- (b) and wherein said fluid inlet is normally a higher pressure flow than said low pressure fluid outlet,
- (c) a valve chamber within said valve housing in communication with both said inlet and said outlet,
- (d) first control member sealed in said valve chamber communicating said chamber with said inlet and outlet and in one direction adapted to increase the flow through said outlet and in the other direction adapted to restrict the flow, said first control member separating said chamber into two parts,
- (e) an orifice normally closed by the operation of said

- first member and said member being freely movable under pressure and being biased in one direction or the other by the pressure thereon,
- (f) a second control member on said valve having a portion thereof in communication with said inlet in certain positions thereof and arranged to close selectively a secondary flow orifice independently of said primary flow orifice controlled by said first control means,
- (g) a first solenoid control valve means for causing motion of said secondary flow means to operate said secondary control in said orifice as when leveling said elevator,
- (h) secondary solenoid control means actuatable to operate said secondary flow control,
- (i) first solenoid control means actuatable to operate said first control means thereby to open said main flow as when said elevator is thereby establishing the down speed of the elevator.
18. In a control valve for controlling the flow in a pressure fluid system such as a control system for controlling the descent and leveling of an elevator by a hydraulic system in which there is a jack cylinder and elevator piston operated by fluid delivered under pressure from a fluid reservoir,
- (a) a valve housing having a chamber therein with an outlet leading to the reservoir and an inlet to said chamber leading from the pressure line,
- (b) said chamber having a first variable orifice formed therein with means thereon to pre-adjust same differently than a
- (c) second variable orifice in said chamber,
- (d) a first control member in said chamber freely floating but biased and operated by an imbalance of pressure thereon to move from a main line flow to a restrictive flow position,
- (e) a pilot flow means on said chamber to cause an imbalance on said first control in response to a
- (f) first solenoid control means for said pilot flow,
- (g) means for adjusting the rate of flow of said first control means,
- (h) said first control means opening in response to said first solenoid to establish the down speed of the elevator,
- (i) a second solenoid control valve,
- (j) a second pilot flow through said second solenoid control valve operable at the time said first control valve is de-energized to change the imbalance force on said first control means to cause same to close off the main flow,
- (k) and means operable upon the energization of said first solenoid control valve and energization of said second control valve to cause an imbalance on said secondary control means to open the secondary flow thereby to permit said elevator to decelerate from full down speed to leveling speed,
- (l) said elevator continued to level down until the second solenoid control valve is operated to bring said system to rest.

19. In a control valve for controlling the flow in a pressure fluid system such as a control system for controlling the ascent, descent and leveling of an elevator by a hydraulic system in which there is a jack cylinder and elevator piston operated by fluid delivered under pressure from a fluid reservoir,
- (a) a valve housing having a chamber therein with an outlet leading to the reservoir and an inlet to said chamber leading from the pressure line,
- (b) said chamber having a first variable orifice formed therein with means thereon to pre-adjust same differently than a
- (c) second variable orifice in said chamber,
- (d) a first control member sealed and dividing said chamber and operated by an imbalance of pressure thereon to move from a main line flow to a restrictive flow position, said member being free floating and biased by pressure.
- (e) a pilot flow means on said chamber to cause an imbalance on said first control in response to a
- (f) first solenoid control means for said pilot flow,
- (g) means for adjusting the rate of flow of said first control means,
- (h) said first control means opening in response to said first solenoid to establish the down speed of the elevator,
- (i) a second solenoid control valve,
- (j) a second pilot flow through said second solenoid control valve operable at the time said first control valve is de-energized to change the imbalance force on said first control means to cause same to close off the main flow,
- (k) means operable upon the energization of said first solenoid control valve and energization of said second control valve to cause an imbalance on said secondary control means to open the secondary flow thereby to permit said elevator to decelerate from full down speed to leveling speed,
- (l) said elevator continued to level down until the second solenoid control valve is operated to bring said system to rest,
- (m) a second member in said chamber and being biased and free floating independently of said first member to open and/or close said second variable orifice for leveling speed,
- (n) said second member being imbalanced by a change of pressure thereon caused by the operation of the pilot flow in response to selection of said first and second control valves.
